UNITED STATES PATENT OFFICE.

WILLIAM B. CAROLUS, OF STERLING, ILLINOIS.

BOLT AND NUT CUTTER.

SPECIFICATION forming part of Letters Patent No. 790,617, dated May 23, 1905.

Application filed March 3, 1903. Serial No. 145,882.

To all whom it may concern:

Be it known that I, WILLIAM B. CAROLUS, a citizen of the United States, residing at Sterling, in the county of Whiteside and State of Illinois, have invented a new and useful Improvement in Bolt and Nut Cutters, of which the following is a specification.

My invention relates particularly to combination bolt and nut cutters of the character described in my United States Patent No. 710,182, granted September 30, 1902.

My primary object is to provide improved means for preventing racking or displacement of the swinging blades employed and also to provide an improved construction of the blades, permitting the use of the implement in places difficult of access.

The invention is illustrated in the accompanying drawings, in which—

20 Figure 1 represents a broken plan view of the improved device; Fig. 2, a similar view with the top plate of the frame removed; Fig. 3, a longitudinal sectional view taken as indicated at line 3 of Fig. 1; Fig. 4, a transverse sectional view taken as indicated at line 4 of Fig. 1, and Fig. 5 a transverse section taken as indicated at line 5 of Fig. 1.

The preferred construction is as follows:

25 A A' represent a pair of swinging bolt-cutting blades pivotally joined by bolts *a* to connecting-plates *a'* *a''*, constituting a frame for the head of the instrument; B B', levers pivotally joined together at *b* and connected by pivots *b'* with the base ends of the blades, and C a blade-controlling member preventing racking or displacement of the blades. The blades are provided with cutting edges *c* and have beveled surfaces *c'* on their upper surfaces. At their extremities the blades are 30 provided with upturned blades *d*, having bolt-cutting edges *d'*. Surmounting the blades *d* are nut-splitting blades *f*, having vertical edges *f'* *f''*, the latter being slightly rounded or blunt.

45 The plates *a'* *a''* are preferably stamped from sheet metal and are extended rearwardly a sufficient distance to house the pivotal ends of the hand-levers B B'. They are provided with slots *g*, in which works the pivotal bolt *b*, connecting the levers.

The member C comprises a head *h*, having lateral projections *h'*, with rounded surfaces fitting in suitably-concaved bearings *h''*, with which the blades A A' are provided, and a stem *h''*, equipped at its rear extremity with upper and lower projections *h''*, working in longitudinal guides *h''*, with which the plates or scales *d'* *d''* are provided. The pivots *b'* are headless pins confined in place by the plates. The bolt *b* is suitably shouldered at its connection with the nut to prevent binding upon the plates.

For the purpose of enabling the device to be used in places where the bolt cannot readily be seen—as, for instance, beneath the flange 65 of a stove-top—I provide a yielding gage or stop D, which is carried by the plate *a'*. This comprises a shank *g*, connected with said plate, and an upturned extremity *g'*, spaced at a suitable distance from the vertical blades of 70 the device. The stem *g* is provided with a longitudinal slot *g''*, which is slidably connected with an adjustable block *g''*, secured to the plate by a screw *g''*, which extends through a slot in the block *g''*. Confined between the 75 front edge of the block *g''* and the front end of the slot *g''* is a spring *g''*. This spring normally holds the gage in its forward position, the position being determined by the adjustment of the block *g''*, with the rear edge of 80 which the rear end of the slot *g''* is in normal engagement. When a nut is to be split, the instrument is shoved forward till the flange *g'* of the gage engages one edge of the nut, in which position the edges of the blades *f* 85 are located properly to split the nut. The edge *f''*, being somewhat blunt, acts as a pivot about which the halves of the nut turn when the nut is split by the edge *f'*.

In use either the edges *c* or the edges *d'* 90 may be employed for clipping a bolt, according to convenience. In splitting a nut the edges *f'* *f''* are employed as described. In the closed position of the blades the edges *f'* *f''* are separated by a space corresponding 95 with the diameter of the bolt. The member C acts to aid the pivots *a* in preventing separation of the blades and also acts to prevent one blade from working forward with relation to the other, the stem of the member C 100

being prevented from turning by reason of the connection with the guides h^5 , which guides permit the necessary relative movement between the member C and the plates $a' a^2$.

5. While I have shown the nut-splitting blades formed integrally with the bolt-cutting blades, it is obvious that they may be separately formed and may be adjustable with relation to the bolt-cutting blades.
10. Changes in minor details of construction within the spirit of my invention may be made. Hence no undue limitation should be understood from the foregoing detailed description.
15. What I regard as new, and desire to secure by Letters Patent, is—
1. An implement of the character described, comprising pivoted blades with cutting edges lying in one plane and nut-splitting blades at 20 right angles to and carried by the extremities of said first-named blades, and having their splitting edges in the closed position separated by a space for the bolt, for the purpose set forth.
  25. 2. An implement of the character described, comprising pivoted bolt-cutting blades with cutting edges lying in one plane, bolt-cutting blades at right angles to and carried by the extremities of said first-named blades, and 30 nut-splitting blades adjacent to said second-named blades and at right angles to said first-named blades.
  35. 3. An implement of the character described, comprising swinging blades, a frame in which said blades are pivoted, hand-levers connected with said blades, and a member interposed between said blades having bearings therein and movably connected with said frame, for the purpose set forth.
  40. 4. An implement of the character described, comprising swinging blades, a frame in which said blades are pivoted, hand-levers connected with said blades, and a member interposed between said blades having bearings therein 45 and provided with a projecting stem slidably connected with said frame.
  45. 5. An implement of the character described, comprising swinging blades, a frame in which said blades are pivoted, hand-levers connected with said blades, and a member interposed 50 between said blades and provided with convex enlargements fitting within cavities in the

adjacent portions of said blades and tending to prevent separation of the blades and longitudinal movement of the blades with relation 55 to each other.

6. An implement of the character described, comprising suitable plates, blades between said plates and pivoted therein, hand-levers pivoted between said plates and connected by a 60 pivot slidably connected with said plates, and a member confined between said blades and said plates and having bearings in the blades between the pivots thereof and provided with a stem slidably connected with a plate, for the 65 purpose set forth.

7. An implement of the character described, comprising pivoted cutting-blades, cutting-blades carried thereby and projecting at right angles thereto, means for operating the blades, 70 and a suitably-supported gage adjacent to said second-named blades and on the side thereof toward the base ends of the first-named blades, for the purpose set forth.

8. An implement of the character described, 75 comprising a suitable frame, blades pivoted therein, hand-levers for actuating said blades, blades at right angles to said first-named blades and carried by the extremities thereof, and a gage yieldingly supported on said frame, 80 for the purpose set forth.

9. In an implement of the character described, the combination of two suitably-spaced plates provided with a longitudinal guide, blades between said plates and pivoted 85 thereto, a member located between said blades and having bearing connections therewith between the pivots thereof and provided with a stem slidably connected with said guide, and hand-levers pivotally connected with said 90 blades and connected by a pivot moving in longitudinal guides in said plates, for the purpose set forth.

10. An implement of the character described, comprising a frame with suitable 95 sides, blades between and pivoted to said sides, hand-levers joined to said blades by pivots confined by said sides, and a pivot connecting said hand-levers and moving in guides in said sides.

WILLIAM B. CAROLUS.

In presence of—

A. C. KITTLESON,
WALTER N. WINBERG.
